CLAIM

The ornamental design for a pants zipper, as shown and described.

DESCRIPTION

FIG. 1 is a perspective view of the pants zipper showing my new design;

FIG. 2 is a front view thereof;

FIG. 3 is an enlarged view of the pants zipper taken from FIG. 2;

FIG. 4 is a right-side view thereof;

FIG. 5 is a left-side view thereof;

FIG. 6 is a top view thereof;

FIG. 7 is a bottom view thereof;

FIG. 8 is a back view thereof;

FIG. 9 is a perspective view of an alternative embodiment of the pants zipper;

FIG. 10 is a front view thereof;

FIG. 11 is an enlarged view of the pants zipper taken from FIG. 10

FIG. 12 is a right-side view thereof;

FIG. 13 is a left-side view thereof;

FIG. 14 is a top view thereof;

FIG. 15 is a bottom view thereof; and,

FIG. 16 is a back view thereof.
